**COMBINED ELECTRIC CAN OPENER AND
KNIFE SHARPNER**

Henry J. Talge, Kansas City, Mo., assignor to
John C. Hockery, trustee, Kansas City, Kans.

Filed Nov. 16, 1962, Ser. No. 72,511

Term of patent 14 years

(Cl. D37—1)

Fig. 1.

Fig. 2.

Fig. 3.

Fig. 4.

Fig. 5.

FIG. 1 is a front elevational view of a combined electric can opener and knife sharpener embodying my new design;

FIG. 2 is a top plan view of same;

FIG. 3 is a rear elevational view of same;

FIG. 4 is a side elevational view of same taken from the left-hand side of FIG. 1; and

FIG. 5 is a side elevational view of same taken from the right-hand side of FIG. 1.

I claim:

The ornamental design for a combined electric can opener and knife sharpener, as shown.
